FEED MECHANISM FOR NIPPLE THREADING MACHINES AND THE LIKE

George B. Marsden, Chicago, Ill., assignor to
 Chicago Nipple Manufacturing Company,
 Cicero, Ill., a corporation of Delaware

Application September 27, 1950, Serial No. 187,091

12 Claims. (Cl. 10—105)

1

This invention relates to feed mechanism for nipple threading machines and the like, and particularly to a mechanism for advancing nipple blanks and like work pieces into a rotating cutter and retracting the finished pieces therefrom.

It is one of the objects of the invention to provide a feeding mechanism in which the blank is advanced rapidly to a point adjacent the cutting head and is then fed slowly into the head at a rate synchronized with the rotation of the head. According to one feature, the feed is entirely mechanical to produce a relatively simple mechanism which can operate accurately at high speed.

Another object is to provide a feeding mechanism in which rapid movement of the blank is produced by a rotating cam intermittently driven over a predetermined angle by a single revolution clutch.

Still another object is to provide a feeding mechanism in which the carriage is detachably coupled to the slow feeding mechanism at the end of its rapid movement. In the preferred construction, the slow feed mechanism is started at the same time coupling is effected to advance the work piece into the cutting head.

A further object is to provide a feeding mechanism in which the slow feed is effected by a screw device driven in synchronism with the cutting head and preferably at a rate slower than the rate of rotation of the cutting head.

A still further object is to provide a feeding mechanism in which the operation may be performed automatically in a predetermined sequence.

The above and other objects of the invention will become more readily apparent from the following description when read in connection with the accompanying drawing in which

Figure 1 is a side elevation of a nipple threading machine having a feeding mechanism embodying the invention;

Figure 2 is a partial section on the line 2—2 of Figure 1;

Figure 3 is a section on the line 3—3 of Figure 1;

Figure 4 is a horizontal section on the line 4—4 of Figure 3; and

Figure 5 is a partial section taken immediately above the cam device and showing the cam device.

The complete machine as best seen in Figure 1, comprises a frame or base 10 which may be a table-like member supported at a desired con-

2

venient height above the floor on legs 11. The frame 10 carries a pair of rotatable cutter heads or chasers 12 which may be of conventional construction, equipped with cutting tools to thread the ends of nipple blanks fed into them. The tools are preferably movable inward to a cutting position and outward to a release position for rapid removal of a finished blank by means of a lever 13 pivoted on each of the heads. 5 When the lever is thrown to its counterclockwise position shown in Figure 1, the cutters are moved inward to their cutting position. At the end of a cutting operation the end of a nipple blank will engage a trip lever in the head to release the cutters and move them outward, at the same time swinging the lever 13 clockwise. This construction is conventional and will not be illustrated or described in further detail.

Each of the cutting heads is carried by a 10 horizontal rotating shaft mounted in a bearing block 14 on the frame. The heads are driven through sprockets 15 secured to the shafts and engaged by sprocket chains 16 which are driven by sprockets 17 on a variable speed reducer 18 15 mounted on supports above the frame. The reducer is driven through a sprocket 19 connected by a chain 21 to a driving sprocket carried by a main driving motor 22 supported below the reducer. Thus when the motor is running the heads will be turned at a speed determined 20 by the adjustment of the variable reducer 18.

At its end opposite the mechanism which is described, the frame carries guideways 23 on which a carriage 24 is slidable toward and away from the heads. The carriage carries a pair of 25 chucks 25 which are rotatable on vertical axes and are controlled through cam mechanism co-operating with tracks on the frame and through spring units 26 to turn between an aligned feeding position when remote from the heads to 30 parallel cutting positions as they move toward the heads.

When in the feeding position, nipple blanks 35 may be fed into the chucks and finished blanks ejected therefrom through a cross feed mechanism carried by a framework 27 mounted on the frame 10. The carriage and cam control and cross feed mechanism are more particularly described and claimed in my co-pending applications Ser. No. 95,636, filed May 27, 1949 and Ser. No. 172,660, filed July 8, 1950. Since these mechanisms per se form no part of the present invention, they will not be further illustrated or described herein.

According to the present invention, the car-

riage is advanced rapidly to a position adjacent to the heads and is retracted rapidly from the heads at the completion of a cutting operation by a cam mechanism including a rotating cam carried and driven by a central vertical shaft 28 extending upward through the frame. Above the base of the frame the shaft 28 carries a central external cam 29 which is generally spiraled and extends throughout approximately 180° and falls off sharply to its starting position. Facing and opposite to the cam 29 and also rigidly connected to the shaft 28 is an internal cam flange 31 which is spaced from the low side of the cam 29 to receive relatively closely between them a cam follower roller 32. At the high side of the cam 29 the spacing is greater as seen in Figure 4 so that the roller can move away from the cam 29 a distance corresponding to the desired thread length before engaging the flange 31.

The cam is driven from the motor 22 through a gear reducer 33 driven by a sprocket chain 34 from the motor. The reducer 34 drives a sprocket 35 through a single revolution clutch 36, which turns through a complete revolution each time it is engaged and then automatically disengages. The sprocket 35 drives a bevel gear 37 through a sprocket chain 38 and the bevel gear meshes with a pinion at the upper end of a shaft 39 to drive the shaft. Below the frame 10 the shaft 39 carries sprocket wheels driving sprocket chains 41 which in turn, mesh with sprocket wheels on the lower end of the shaft 28. As best seen in Figure 4, the sprocket wheels on the shaft 39 are smaller than the sprocket wheels on the shaft 28 so that the shaft 28 will be turned through 180° each time the clutch 36 is engaged.

Engagement of the clutch 36 is controlled by a solenoid 42 mounted on the frame and connected through suitable linkage to the clutch. The solenoid 42 is controlled by switches not shown, which can be operated manually to initiate operation of the apparatus, or which can be controlled automatically at the completion of a cycle of operations to initiate a succeeding cycle.

The cam follower roller 32 is carried by a slide 43 which is slideable longitudinally on the frame 10 in guide ways 44. Thus, as the cam is turned the slide 43 will be shifted longitudinally of the frame by the cam and is connected to the carriage to move it. As shown, a rod 45 is connected to the carriage and extends between and beyond the heads where it carries a vertical cross pin 46. The cross pin fits in elongated slots 47 in the ends of a pair of levers 48 which are pivoted at their outer ends to fixed pivots adjacent the sides of the frame. The levers 48 are formed intermediate their ends, with elongated slots to receive pins 49 carried by a cross bar 51 which is secured to the slide 43. With this mechanism as the slide moves it will provide a multiplied movement of the rod 45 and the carriage.

When the carriage is moved to its extreme forward position by the cam mechanism as described above, the chucks are adjacent to but spaced from the heads so that nipple blanks or similar work pieces carried by the chucks will not enter the heads. The final feeding movement during actual cutting is performed by a slow feed mechanism which is designed to feed the work pieces into the heads at a rate synchronized with their rotation. The slow feed mechanism as shown, comprises a screw mechanism including a hollow internally threaded nut body 52 which is formed for detachable mounting on the end of the frame remote from the carriage. A threaded shaft or

screw 53 is threaded into the nut body and is recessed at one end to receive the end of a driving shaft 54 carried by the frame. The driving shaft and the recess in the screw shaft may be splined so that the screw shaft will be rotated and can move longitudinally in the nut body, moving the driving shaft 54 with it. The screw shaft is normally urged in one direction by a weight connected to a rack 55 meshing with elongated teeth on the shaft 54. The rack is so arranged that the weight thereon turns the screw shaft in a direction to move it way from the heads or to the left as seen in Figure 1.

The screw shaft 53 is connected through a releasable coupling 56 to a shaft 57 which is swiveled in a rotatable sleeve 58. The sleeve 58 is slidably and rotatably mounted in a bearing block 59 on the frame so that it can move longitudinally as the screw mechanism operates but will not be turned by turning of the shaft 57. At its outer end the sleeve 58 is formed with bayonet slots 61 to receive a pin carried by a reduced extension 62 on the rod 45 when the carriage is advanced toward the heads.

To connect the sleeve 58 to the extension 62, the sleeve is adapted to be rotated to move the pin carried by the extension 62 into the bayonet slots. For this purpose the end of the sleeve 58 is formed with elongated gear teeth meshing with a rack 63 which is adapted to be shifted transversely of the frame. The rack normally holds the sleeve 58 in the position shown in Figure 4, and is adapted to turn it to connect the extension 62 and sleeve 58 when the rack is shifted upward as seen in Figure 4. The shaft 54 and screw shaft 53 are driven through a sprocket 64 connected or splined on the shaft 54 and connected through a chain 65 to a sprocket 66. The sprocket 66 is driven through a clutch 67 which is normally disengaged and which is engaged when a control rod 68 thereon is shifted to the left as seen in Figure 4. The clutch is driven through a chain 69 and sprockets carried by the clutch input shaft and an extension 71 on one of the head driving shafts. In this way, when the clutch 67 is engaged the screw shaft 53 will be driven at a rate proportional to the rate of rotation of the heads in a direction to move the carriage toward the heads. Preferably, the sprockets provide a speed reduction so that the screw shaft will turn slower than the heads at a speed on the order of one-quarter to one-half of the head speed. This enables relatively coarse and strong threads to be employed in the screw feed mechanism while maintaining an accurate relationship between the movement of the carriage in response to the screw mechanism and the cutting rate of the heads.

The clutch 67 is engaged and the sleeve 58 is turned through an air cylinder 72 mounted on the frame and connected at one end to a lever 73 which is pivoted at one end on the frame. The lever is connected intermediate its ends to the clutch control rod 68 and is connected at one end through a push rod 74 to a bell crank lever 75 which is pivoted to the rack 63. When air is admitted to the air cylinder 72 which may be under the control of an electrically operated valve not shown, the lever 73 will be swung counter-clockwise to engage the clutch and to shift the rack in a direction to couple the sleeve 58 to the extension 62.

In operation of the mechanism assuming that blanks have been properly supplied to the chucks, the solenoid 42 is energized to engage the single

5

revolution clutch 36. Through this clutch the cam 29 will be driven counterclockwise through 180° from its initial position shown in Figure 4 to move the carriage toward the heads to a point where the work pieces carried by the chucks are just ready to enter the heads. At this point the rod extension 62 will move into the sleeve 58 so that the pin carried by the rod extension is aligned with the bayonet slots.

When the carriage reaches its forward position described it may operate a switch 76 mounted on the frame which admits air to the cylinder 72 to engage the clutch 67 and turn the sleeve 58. As the screw feed mechanism is driven through the clutch 67 it will advance the carriage further toward the heads to move the work pieces into the heads at a rate synchronized with their rotation so that threads can be formed accurately on the blanks.

When the threading is completed, the heads will be tripped through their internal mechanism or by engagement of an adjustable stop 77 carried by a trip bar 78 secured to the carriage with the trip lever 13 to rock the lever 13 clockwise. This movement of the lever may control switches which deenergize the air cylinder 72 and energize the solenoid 42 to re-engage the single revolution clutch 36. When the air cylinder 72 is de-energized or reversed, it will release the clutch 67 and will turn the sleeve 58 in a direction to disconnect it from the extension 62. When the clutch 67 is released, the rack 55 and its associated weight will turn the screw shaft 53 back to the initial starting position ready for a subsequent operation.

Engagement of the clutch 36 will turn the cam shaft 28 and the cams carried thereby through an additional 180° counterclockwise as seen in Figure 4. During this movement the curved flange 31 will engage the follower roller 32 and will move the carriage away from the heads back to its feeding position. When the carriage is moved to its feeding position a shoulder 79 on the trip bar will rock the lever 13 counterclockwise to close the head ready for a subsequent operation. As soon as the completed work piece is removed and an additional blank is fed into the chucks the mechanism is ready for a subsequent operation which may be initiated automatically through the feed mechanism described in application Ser. No. 172,660. Thus, the machine can be made fully automatic if desired.

Due to the fact that rapid movement of the carriage is effected mechanically through the cam mechanism, the carriage can be moved at a relatively high rate under accurate control and without danger of over-shooting which might damage the heads. The final feed mechanism is accurately synchronized with the rotation of the heads so that the threads are not loaded during cutting and can be formed with a high degree of accuracy. For different sizes of nipples having threads with different pitches the machine can be adjusted by changing the driving ratio between the shaft extension 71 and the shaft 54 or by exchanging the screw mechanism so that a large range of nipple sizes can be accommodated.

While one embodiment of the invention has been shown and described in detail, it will be understood that this is illustrative only and is not to be taken as a definition of the scope of the invention, reference being had for this purpose to the appended claims.

What is claimed is:

1. Feeding mechanism for nipple threading

6

machines and the like comprising a frame, a rotatable cutting head on the frame, a carriage slideable on the frame toward and away from the head, rotatable cam device and a cam follower, one on the carriage and the other on the frame to move the carriage toward the head, the cam device having inner and outer cam surfaces engageable with the follower to shift the carriage positively toward and away from the head, the portions of the cam surfaces which register with the follower when the carriage is adjacent to the head being spaced apart farther than the thickness of the follower so that the carriage and follower can move farther toward the head, drive means intermittently to turn the cam through half revolutions, supplementary feed means effective when the cam has moved the carriage toward the head to move the carriage farther toward the head, and control means operable at the end of a threading operation to energize the drive means.

2. Feeding mechanism for nipple threading machines and the like comprising a frame, a rotatable cutting head on the frame, a carriage slideable on the frame toward and away from the head, a rotatable cam device and a cam follower, one on the carriage and the other on the frame to move the carriage toward the head, the cam device having inner and outer cam surfaces engageable with the follower to shift the carriage positively toward and away from the head, the portions of the cam surfaces which register with the follower when the carriage is adjacent to the head being spaced apart farther than the thickness of the follower so that the carriage and follower can move farther toward the head, a single revolution clutch connected to the cam to turn it through a half revolution each time the clutch is engaged, means to engage the clutch, supplementary feed means effective when the cam has moved the carriage toward the head to move the carriage farther toward the head, and control means operable at the end of a threading operation to operate the means to engage the clutch.

3. Feeding mechanism for nipple threading machines and the like comprising a frame, a rotatable cutting head on the frame, a carriage slideable on the frame toward and away from the head, a rotatable cam device and a cam follower, one on the carriage and the other on the frame to move the carriage toward the head, the cam device having inner and outer cam surfaces engageable with the follower to shift the carriage positively toward and away from the head, the portions of the cam surfaces which register with the follower when the carriage is adjacent to the head being spaced apart farther than the thickness of the follower so that the carriage and follower can move farther toward the head, a single revolution clutch connected to the cam to turn it through a half revolution each time the clutch is engaged, means to engage the clutch, a feed screw, drive means for the feed screw, a releasable coupling to connect the feed screw to the carriage to move the carriage toward the head, means operable when the cam has moved the carriage toward the head to engage the coupling and energize the feed screw drive means, and control means operable at the end of a threading operation to release the coupling, de-energize the feed screw drive means, and engage the clutch.

4. Feeding mechanism for nipple threading machines and the like comprising a frame, a ro-

tatable cutting head on the frame, a carriage slideable on the frame toward and away from the head, feed means to advance the carriage rapidly toward the head to a point spaced therefrom, a positive feed device for moving the carriage relatively slowly from said point further toward the head, a coupling element on the positive feed device, a second coupling element carried by the carriage to engage said first named coupling element when the carriage is advanced to said point and means to move one of the coupling elements to interlock it with the other when the carriage reaches said point, the coupling elements including means to prevent relative longitudinal movement thereof when they are interlocked.

5. Feeding mechanism for nipple threading machines and the like comprising a frame, a rotatable cutting head on the frame, a carriage slideable on the frame toward and away from the head, feed means to advance the carriage rapidly toward the head to a point spaced therefrom, a positive feed device for moving the carriage relatively slowly from said point further toward the head, a coupling element on the positive feed device, a second coupling element carried by the carriage to engage said first named coupling element when the carriage is advanced to said point, drive means for the positive feed device, and control means to energize the drive means and move one of the coupling elements to interlock it with the other when the carriage reaches said point the coupling elements including means to prevent relative longitudinal movement thereof when they are interlocked.

6. Feeding mechanism for nipple threading machines and the like comprising a frame, a rotatable cutting head on the frame, a carriage slideable on the frame toward and away from the head, feed means to advance the carriage rapidly toward the head to a point spaced therefrom, feed screw mechanism including relatively rotatable screw and nut members to move the carriage relatively slowly from said point further toward the head, one of said members being mounted on the frame to be held against longitudinal movement thereon, a coupling element connected to the other member of the feed screw mechanism, and a second coupling element carried by the carriage to engage and interlock with said first named coupling element when the carriage is advanced to said point the coupling elements having means thereon to prevent relative axial movement thereof when they are interlocked.

7. Feeding mechanism for nipple threading machines and the like comprising a frame, a rotatable cutting head on the frame, a carriage slideable on the frame toward and away from the head, feed means to advance the carriage rapidly toward the head to a point spaced therefrom, feed screw mechanism including relatively rotatable screw and nut members to move the carriage relatively slowly from said point further toward the head, one of said members being mounted on the frame to be held against longitudinal movement thereon, a coupling element connected to the other member of the feed screw mechanism, a second coupling element carried by the carriage to engage and interlock with said first named coupling element when the carriage is advanced to said point, drive means for the feed screw mechanism, and control means to start the drive means when the carriage reaches said point the coupling elements having means there-

on to prevent relative axial movement thereof when they are interlocked.

8. Feeding mechanism for nipple threading machines and the like comprising a frame, a rotatable cutting head on the frame, a carriage slideable on the frame toward and away from the head, feed means to advance the carriage rapidly toward the head to a point spaced therefrom, a positive feed device for moving the carriage relatively slowly from said point further toward the head and including a part which is movable longitudinally on the frame at a positive rate, a rotatable coupling element connected to the feed device part, a complementary coupling element connected to the carriage, one of the coupling elements being tubular to receive the other and the elements being formed with parts to interlock to prevent relative axial movement therebetween upon relative rotation thereof, and means to rotate the first named coupling element when the carriage reaches said point to interlock the coupling elements.

9. Feeding mechanism for nipple threading machines and the like comprising a frame, a rotatable cutting head on the frame, a carriage slideable on the frame toward and away from the head, feed means to advance the carriage rapidly toward the head to a point spaced therefrom, a positive feed device for moving the carriage relatively slowly from said point further toward the head and including a part which is movable longitudinally on the frame at a positive rate, a rotatable coupling element connected to the feed device part, a complementary coupling element connected to the carriage, one of the coupling elements being tubular to receive the other and the elements being formed with parts to interlock to prevent relative axial movement therebetween upon relative rotation thereof, drive means for the feed device, and control means operable when the carriage reaches said point to rotate the first named coupling element to interlock the coupling elements and energize the drive means.

10. Feeding mechanism for nipple threading machines and the like comprising a frame, a rotatable cutting head on the frame, a carriage slideable on the frame toward and away from the head, feed means to advance the carriage rapidly toward the head to a point spaced therefrom, feed screw mechanism including relatively rotatable screw and nut members one of which is fixed to the frame, a releasable clutch for rotating the other member, means yieldingly urging the other member in one direction when the clutch is released, coupling means to connect the other member to the carriage, and control means to engage the coupling means and engage the clutch when the carriage reaches said point.

11. Feeding mechanism for nipple threading machines and the like comprising a frame, a rotatable cutting head on the frame, a carriage slideable on the frame toward and away from the head, feed means to advance the carriage rapidly toward the head to a point spaced therefrom, feed screw mechanism including relatively rotatable screw and nut members one of which is fixed to the frame, a releasable clutch for rotating the other member, means yieldingly urging the other member in one direction when the clutch is released, complementary coupling elements connected to the other member and the carriage formed with parts to interlock upon relative rotation, the coupling element connected to the other member being rotatable, and control means to rotate the last named coupling element

and engage the clutch when the carriage reaches said point.

12. Feeding mechanism for nipple threading machines and the like comprising a frame, a rotatable cutting head on the frame, a carriage 5 ₁₀ ₁₅ ₂₀ ₂₅ ₃₀ ₃₅ ₄₀ ₄₅ ₅₀ ₅₅ ₆₀ ₆₅ ₇₀ ₇₅ ₈₀ ₈₅ ₉₀ ₉₅ ₁₀₀ ₁₀₅ ₁₁₀
